COMBINED COIL WINDING AND STRETCHING MACHINE

John Wahlberg, East Orange, N. J., assignor to
Westinghouse Lamp Company, a Corporation
of Pennsylvania

Application June 29, 1931. Serial No. 547,526

16 Claims. (Cl. 153—65)

The present invention relates to the manufacture of electrical devices such as incandescent electric lamps or the like and relates more particularly to the formation of coiled filaments of definite length for use in such devices.

Incandescent electric lamps are manufactured with the light source or filament either in the form of a straight relatively long refractory wire or with a coiled filament comprising a fine refractory wire wound to helical form.

The present invention is concerned with the coiled type of filament which is generally known as a concentrated light source and employed either in a gas filled or an evacuated bulb. The production of coiled lamp filaments to provide a light source includes an important step in the operation of lamp making and such filaments are formed by either of two general winding methods.

First the method of winding a filament wire upon a mandrel cutting the mandrel supported helix into definite lengths or sections and subsequently removing the mandrel to provide coiled filamentary sections to constitute lamp filaments. The second method comprises the operation of coiling a filamentary wire to helical form in the absence of a mandrel, which filament is severed into sections of proper length.

When a light source or filamentary section is produced for use in a lamp of a given wattage certain conditions must be carefully observed as for example the length of the selected filamentary wire contained in the light source must be exact so that the proper resistance will be obtained for a given wattage lamp.

Furthermore each length of filament must contain a helix having a given number of turns and the pitch of the helix must be maintained uniform and the outside diameter held constant.

Although it is possible to provide coiled filamentary sections having a definite length of wire therein, it is not always practical to produce these coiled sections having uniform over-all lengths, that is, the length measured between the end turns. Under ordinary conditions, if filamentary sections are produced so as to contain uniform amounts of wire therein and with the pitch and diameter of uniform dimensions, such filaments will answer all requirements which heretofore attended lamp manufacture when the filaments were mounted by hand. Commercial conditions, however, demanding low cost of production make it necessary to speed up operations and it has become desirable to provide machines for automatically mounting coiled sections.

Mechanism has been devised for automatically handling the coiled sections, positioning them with respect to the lead wires or conductors of a lamp mount or stem and for clamping or welding the ends of the lead wires to the ends of the filament. This automatic mechanism makes it necessary to maintain filamentary sections of uniform over-all lengths, so that when positioned to be received by the automatic mounting mechanism, including means such as pairs of jaws which grip the ends of the filament, these jaws may be given a fixed position and the filaments or coiled sections may be fed thereto without a failure of the jaws to grip the filament by reason of either too long or too short filament lengths.

It will be evident that where the jaws are positioned to grip a filamentary section of a certain length, any variation in this filament length will result in the jaws either failing to grip the end of the filament or in the application of too great a portion of the filament being compressed between the jaws.

For the purpose of producing filaments with predetermined over-all lengths it has been found desirable to produce a filament of a given pitch and length and thereafter stretch the filament to a predetermined pitch and length.

One type of machine for accomplishing a coil stretching operation is shown and described in Patent 1,830,222 for Machine for stretching coils which patent is assigned to the present assignee. Although the machine disclosed in the above mentioned patent has been found satisfactory to stretch coiled sections, it has become desirable to provide a more compact mechanism including certain improvements in the construction of parts and so proportioned and arranged as to be applicable as a part of a coil winding machine preferably a mandrelless coil winding machine, such for example as that shown in Patent 1,670,499 of May 22, 1928.

It is an object of the present invention to provide a simple and compact coil winding and stretching mechanism.

Another object of the invention is to provide a coil stretching unit operable in conjunction with mechanism for feeding coiled sections.

Another object of the invention is to provide a coil stretching mechanism which may be operated in synchronism with a coil winding machine.

Another object of the invention is to provide a coil stretching mechanism wherein a carrier is intermittently moved with each actuation of mechanism operating to sever and discharge a coiled section.

Other objects and advantages of the invention will be more clearly understood from the following description together with the accompanying drawings in which

5 Fig. 1 is a perspective view of a coil stretching machine in operative relation to a mandrelless coil winding machine.

Fig. 1a is a fragmentary view showing mechanism for severing coiled sections.

10 Fig. 2 is an enlarged vertical sectional view of the coil stretching mechanism as shown in Fig. 1 but without the coil winding mechanism.

Fig. 3 is a view taken on line III—III in Fig. 2.

Fig. 4 is a view taken on line IV—IV in Fig. 2.

15 Fig. 5 is a view taken on line V—V in Fig. 2.

Fig. 6 is a view taken on line VI—VI in Fig. 2.

20 Fig. 7 is an enlarged fragmentary view taken on line VII—VII in Fig. 5, of a part of the coil stretching mechanism showing a coil to be stretched in place and having its ends held between jaws.

Fig. 8 is a view taken on line VIII—VIII in Fig. 7 and Fig. 9 is a view taken on line IX—IX in Fig. 7.

25 Although the present coil stretching mechanism is adapted for use in connection with a mandrelless coil winding machine, it is obvious that the coil stretching mechanism is a complete unit and may be employed in connection with any other mechanism, as for example, means whereby coiled sections are discharged so as to be received by the coil stretching mechanism and also machines wherein the coil discharge means cooperates with the coil stretching mechanism to cause an actuation of the latter. The coil stretching mechanism may of course be operated as a unit and coils may be fed thereto by hand if desirable.

40 For the purpose of clearness the coil stretching mechanism will first be described and subsequently its relation and cooperation with a mandrelless coil winding machine will be set forth.

45 The present coil stretching mechanism is indicated in the drawings as a whole by the letter "A". As clearly shown in Fig. 2 a machine embodying the present invention may comprise a base plate 10 which in the present construction may be of fibre or other insulating material or of molded "bakelite."

50 The base plate may be formed so as to provide a pivoted shelf or support for attachment to a coil winding machine indicated as a whole by the reference letter "B". This machine and the cooperative relation between the same and the coil stretching machine will, as above mentioned, be later described.

55 The base plate is provided with a central spindle 11 on which is mounted by means of a tap bolt, a hub 12 of insulating material having a circular cam track 13 mounted on the flange 14 thereof. The spindle 11 is also provided with an insulative collar 15 to which is secured a flange 16 having an under cam surface 17. A partially grooved or slotted cam 18 is secured to the collar 15. The several cams 13, 17 and 18 may be adjusted vertically by means of a knurled thumb nut 19 having an internal thread 21 to engage with an external thread 22 on the spindle 11. Within the spindle 11 is an adjuster rod 23.

60 The upper end of the rod 23 is provided with a shoulder 25 disposed within an accommodating recess in the thumb nut 19. A tubular extension 75 26 projects from the shoulder 25 through the

thumb and a stop collar 27 is fastened to the end of the projection 26.

A rotation of the thumb nut will raise or lower the adjuster rod and a calibrated gauge block 28 is provided to indicate the degree of movement of the adjuster rod 23. The cams 17 and 18 are secured to the insulative collar 15 by tap bolts 29 which extend through a cylindrical portion 31 of the flange 16 and through a bushing 32 constituting an integral portion of the cam 18. The tap bolts 29 are provided with stem portions 33 disposed in apertures 34 provided in the adjuster rod 23, a slot 35 being provided in the spindle 11 to permit a relative movement of the cams which are movable with the adjuster rod 23.

80 From the above it will be evident that the cams 13, 17 and 18 are mounted on the spindle 11 and are secured against relative rotary movement with respect to the spindle but by reason of the adjusting mechanism may be vertically adjusted 90 relative to the spindle 11.

85 The cams just described are proportioned and arranged to operate mechanism to grip the ends of coiled filamentary sections 36 to be stretched. In performing this stretching operation the coils 100 are held in vertical positions as shown and gripped by jaws of what may be termed coil stretching heads indicated as a whole by the reference letter "C". Any number of these heads may be employed, ten heads being shown in the present construction. The heads are mounted on a carrier indicated as a whole by the reference letter "D" consisting of an upper ring or disc 37 and a lower ring or disc 38 held in space relation by suitable spacer members 39. The discs 37 and 38 may be 110 of suitable insulative material as fibre or a molded condensation product.

105 The carrier "D" may be of circular form having a lower centrally disposed hub 41 which hub in the present construction is threadedly connected 115 at 42 with the disc 38 and is provided with a ratchet wheel 43 and a toothed retainer or index wheel 44. The hub 41 on which the carrier is mounted rotates about the spindle 11. The spindle 11 is provided with a support plate 45 120 seated upon the base plate 10 and a pin 46 is provided to lock the plate 45 to the base plate and prevent a rotation of the spindle 11. The plate 45 cooperates with a clamping plate 45' threadedly connected to the lower end of the spindle 125 11 to hold the spindle in its vertical position. Thus the carrier may be rotated in a series of intermittent movements about the spindle through the action of a pawl cooperating with the coil winding machine in a manner to be later described.

130 As above mentioned a plurality of coil stretching heads are provided and inasmuch as these heads are of similar construction a description of one will answer for all.

135 As shown more clearly in Figs. 2, 7, 8 and 9 the coil stretching device may comprise a telescopic casing 47 which may be made of tubular sections, it having been found that glass tubing is satisfactory although other material may be 140 employed. The casing may comprise an outer or enlarged tubular section 48 having its ends secured in opposed surfaces of discs 37 and 38. Extending into the tube 48 is a lower tubular end piece 49 and at the upper end of the tubing 48 145 is disposed a tubular end piece 51. The tubular pieces 49 and 51 are disposed in telescopic arrangement within the tube 48 and a helical spring 52 disposed within the casing serves to move the tubing 51 to a normal given position.

The coiled section 36 is fed through a chute or guide 53 so that it drops into the casing 47 and within the coiled spring 52. During the operation of stretching the coiled filamentary section 5 electrical energy is passed therethrough as will be later described to heat the same and the spring 52 may, therefore, be provided with an insulative layer as for example it may be covered with a non-conductive shellac or may be oxidized so that in the event that the coiled filamentary section makes contact with the spring the said section will not be short circuited.

The telescopic arrangement of the casing makes it possible to keep the filamentary section entirely enclosed during the stretching operation since by reason of the telescopic arrangement the casing will accommodate itself to the lengthening of the coiled section under the stretching operation.

Each coil stretching device includes upper gripper members 54 and lower gripper members 55. (See Figs. 7 and 8). The lower gripper members are not movable to stretch the coiled section and only operate to grip the lower end of the coil and hold it while the upper gripper members are moved upwardly.

The upper gripper members as shown in Fig. 9 comprise a pair of lever members 56 and 57 pivoted at 58. Arms 59 and 61 of the lever members are provided with a notch 62 and a contact face 63 respectively to grip the end of the coiled section. The levers 56 and 57 of the gripper members are arranged to provide a scissor action so that movement of the arms of a pair toward each other causes a similar movement of the opposite arms.

Arms 64 and 65 of the gripper members are normally urged toward each other by a spring 66 opposite ends of which are secured to opposite arms. The jaws are thus normally urged closed and are opened at the proper time by a pin 67 which is moved between the arms 65 and 64 which pin is carried on a slide plate 63 slidably through a head 69 in which the gripper members are mounted. The pin 67 is so arranged on the slide plate as to engage with cam 18, which cam is provided with a lateral surface 71 to move the pin inwardly between the arms 64 and 65 and a track or guide portion 72 is provided to retract or withdraw the pin thus permitting the jaws to open.

The movement of the slide plate in the head operates to position an aperture 73 provided in the slide plate over the jaws 62 and 63 so that a filamentary section 36 passing from the chute 53 may drop into the casing 47. At the time the aperture 73 is disposed over the jaws the pin 67 operates to maintain the jaws open. When the slide plate 63 retracts, the jaws grip the filamentary section thus leaving it in readiness to be stretched.

The stretching operation is performed by a movement of the head 69 which carries the upper gripper members 54. This head is provided with a plunger 74 extending through a suitable bearing 75 in the disc 37. The lower end 76 of the plunger is disposed in contact with the cam surface 13 so that a relative movement between the plunger and the cam surface will cause the plunger to be elevated thus elevating the head, changing the distance between the gripper members 54 and 55.

The head is lowered by reason of a contact boss 77 disposed for contact with the cam 17.

Before the gripper members 54 are lifted, however, it is obviously necessary that the gripper members 55 secure the lower end of the coiled filamentary section. The lower gripper members, as shown in Fig. 4, may comprise a pair of lever members 78 and 79 pivoted at 81 and having a scissor action.

These jaws are normally held closed by a suitable spring 82 and are caused to open by a movement of pin 83 mounted on a slide plate 84. The slide plate 84 is provided with an aperture 85 and a cam follower 86 arranged to travel in a cam track 87 provided on the base plate 10. The slide plate 84 is normally positioned beneath the jaws so as to provide a support for the end of a filamentary section when it is dropped into the casing 47 which end is thus positioned between the gripping surfaces 88 and 89 of the lower gripper members. As the carrier rotates the cam follower rides in the cam track 87 consisting of guide surfaces 91 and 92 so that the plate 84 will be reciprocated in accordance with the formation of the cam track.

For the purpose of heating the filament to give it what is termed a flashing period thereby annealing the filamentary wire, a resilient contact plate 93 is provided. This contact is carried by posts 94 of insulative material secured in apertures or bores 95 in the base plate 10. The posts 94 are hollow and conductive rods 96 are disposed therein having their upper ends secured by tap bolts 97 to the contact plate 93. The lower ends of the rods are provided with a conductive cross piece 98 and helical springs 99 disposed around the rods, between the cross piece 110 and the under side of the base plate serve to hold the contact plate against the forward ends 101 of the slide plate 68. One of the contact members 96 is provided with a binding post 102 connected by a conductor 103 with one side of 115 a source of electrical current (not shown).

For the purpose of completing the flow of energy through the coiled section 36 a second resilient contact plate 104 is provided to engage with the cam followers 86 which are part of the 120 lower coil gripping members (see Fig. 4). The contact plate 104 may be secured by tap bolts 105 to the base plate and a conductor 106 is provided to complete the electrical circuit in conjunction with the conductor 103. In order to 125 avoid short circuiting between the adjacent portions of the machine and the coils through which the electrical energy is to pass, the flange 16 carrying the cam surface 17 is divided to provide segment 106 (see Fig. 6), this segment being 130 spaced from the rest of the flange and insulated by reason of the collar 15 permits the cam to make contact without short circuiting. The cam 18 which actuates the pins 67 is also provided with a segment 107 (see Fig. 5) insulated at 103 135 and 109 from the rest of the cam 18.

The foregoing gives a detailed description of the various operative parts of the coil stretching device and before describing the same in connection with the coil winding machine the following 140 description relating to the operation of the coil stretching machine is given.

Operation of coil stretching mechanism

Referring to Fig. 2 it will be seen that the plate 68 is so positioned as to arrange the aperture 73 beneath the chute 53. When the coil stretching device is aligned with the chute 53 a coiled filamentary section then drops into the casing 47 passing the upper jaws which are open and the 150

lower end of the filamentary section is supported by the lower plate 84, the lower jaws also being opened.

As shown in the drawings, when the filamentary section is received at the loading position the head 69 carrying the upper gripper members is in a raised position. The machine may then be indexed through its cycle in a series of intermittent movements at which time the plunger riding on the cam 13 is allowed to drop thus lowering the head 69 and positioning the gripper jaws around the upper end of the filamentary section 36.

During this movement the upper cam 17 engages the boss 77 so that the downward movement of the head is positive. When the head reaches its lower position the tubular section 51 of the casing 47 moves downwardly in opposition to the action of the spring 52.

While the head is thus lowered the pins 67 are moved in accordance with the cam track 18 and the jaws 61 and 62 are closed to grip the upper end of the filamentary section at which time the cam follower 86 on the lower slide plate moves to cause the pin 83 to move away from between the arms of the gripper members allowing the jaw faces 88 and 89 to grip the lower end of the filamentary section.

During this movement the lower slide plate 84 moves in the direction of the arrow "X" and as the carrier "D" rotates the lower and upper jaw members are separated thereby stretching the filamentary section a predetermined amount which is determined by the amount of raise or drop of the cams 13 and 17 respectively. The vertical positions of these cams may be changed to accommodate different length filamentary sections by a manipulation of the thumb nut 19. The machine may therefore be easily adjusted to stretch filamentary sections for lamps of different wattage.

As the carrier moves and the coiled filamentary section is stretched, the stretched section passes to position between the contact plates 93 and 104 so that electrical energy will pass through the stretched section heating it to give it what is termed a flashing or annealing treatment. As the carrier moves the stretched section to the final or unloading position the cam 18 operates to open the upper gripping jaws and position the slide plate 68 with its aperture in position to admit another coiled filamentary section and the lower slide plate 84 is moved in the direction of the arrow "Y" causing the pin 83 to open the jaws, the movement of the plate being continued until the aperture 85 registers beneath the stretched section as the jaws open, thus releasing the stretched section for discharging into a suitable receptacle 110.

Before the carrier moves the stretching device to position to receive another section, however, the plate 84 moves in the direction of the arrow "X" sufficiently to open the jaws and move the aperture 85 leaving a portion of the plate 84 ready to receive the end of another coiled filamentary section.

Combined coil winding and stretching machine

Referring now to the combined coil winding machine "A" and coil stretching machine "B" the coil winding machine as above mentioned is of the type disclosed in the above mentioned Patent No. 1,795,767 and includes a pair of force rollers 120 and 121; the upper roller 120 being mounted in a bearing plate 122, the lower roller

being mounted in suitable bearings on the frame work 123 of the machine.

The rollers 120 and 121 are driven in opposite directions by suitable means, (not shown) and frictionally engage a filament wire 124 which 80 is drawn from a spool 125 after passing in a bight around a measuring roller or drum 126 which is mounted on a suitable support or bracket 127 secured to a bed plate 128 of the coil winding machine. As the wire passes between 85 rollers 120 and 121 it enters a cavity in one end of a die rod 129. The cavity and the actual end of the die rod are too small for illustration in the present drawings, but this operation is, however, well known in coil winding and clearly 90 shown in the above mentioned patent.

The said die rod is mounted in a holder 131 and is adjustable endwise by means of suitable set screws and is provided with other adjustments for sidewise and vertical movement 95 through the agency of suitable adjusting means. No further description of the actual coil winding mechanism is thought to be necessary.

The present coil stretching mechanism, however, operates in conjunction with the coil cutting mechanism employed as part of the coil winding machine and an improved form of coil cutting mechanism is shown in Patent No. 1,733,620 and is likewise shown in the coil winding machine in the present drawings. 105

The coil cutting mechanism as shown in the above mentioned patent and illustrated herein includes co-related machine elements which operate to sever a coiled section without applying excessive stress on the wire which rotates the 110 measuring drum. In the cutting of coiled sections on the mandrelless coil winding machine, it is desirable to measure the wire previous to cutting and this operation is performed by utilizing the measuring drum to actuate cutter 115 mechanism, thus each coiled section will have therein the same length of wire.

The mechanism shown in Patent No. 1,733,620 is adapted to operate the present coil stretching mechanism since the coil cutting elements shown 120 include a reciprocating member which is utilized to operate a pawl and ratchet which rotates the carrier of the coil stretching machine.

Coil cutting mechanism

The coil cutting mechanism which is in fact a coil discharge mechanism includes a cutter 133 (see Fig. 1a) mounted on a plunger 134 reciprocal vertically in a guide plate 135. Between the wire coiling cavity of the die rod 129 and 130 the cutter is a tubular guide 136 so that the formed continuous coil is guided from the die to the cutter. The lower end 137 of the plunger 134 is disposed in contact with a set screw 138 at one end 139 of a lever member 141 pivoted 135 at 142 in a bearing 143. The opposite end 144 of the lever is provided with a latch 145. This latch consists of a rocker member 146 pivoted at 147 and having an arm 148 normally held against a stop 149 by spring 151 thus an engagement with one end of an arm 152 of the rocker member 146 will serve to depress the opposite end 144, by reason of the stop 149 and rock the lever 141 while an engagement of the opposite side of the arm 152 will permit the 145 rocker member to move without actuating the lever 141.

It will therefore be evident that by engaging the rocker arm 146 the lever 141 may be actuated to lift the plunger 134 and cause the 150

knife or cutter 133 to sever a coil. The knife moves across the orifice at the end of the tube 136 the edge of which serves as a bed knife. A spring 153 disposed between a shoulder 154 and a collar 155 on the plunger operates to normally return the plunger to its lower position. It will be appreciated that the present cutter must sever the coil as it moves from the coil winding die, therefore the action of the cutter must be positive and instantaneous.

In the present invention wherein the coil is inserted into a coil stretching machine the cutter is arranged so as to discharge the coil into the chute 53 and acts as a coil feeding means for the coil stretching machine. The mechanism for severing the coil is, in the present invention, utilized to operate the coil stretching mechanism, i. e., intermittently rotate the carrier and consequently cause the various cams to perform their functions as above described.

The coil severing mechanism which is indicated as a whole by the reference letter "E" may comprise a measuring drum 126 provided with a gear wheel 156 in mesh with a change gear or idler 157 which is disposed in mesh with a gear wheel 158 secured to a shaft 159. The shaft 159 is provided with a cam member 161 having a cam surface 162 and a drop portion 163. The said cam engages a trigger member 164 journaled at 165 in a bearing 166. One end 167 of the trigger is connected by spring 168 to a projection 169, the said spring operating to hold a lug 171 at the opposite end of the trigger member normally engaged with the cam surface 162. On the trigger member opposite to the lug 171 is provided a lug 172 engageable with a lug 173 at the free end of a latch piece 174, the latch piece being pivoted at 175 on a slide plate 176. A spring 177 is provided to normally urge the latch piece against a stop pin 178 so as to be in position to engage the lug 172 of the trigger 164.

The latch piece 174 is mounted on and is movable with the plate 176 which is slidable in guides 179 and 181. It will be understood that the trigger 164 which is mounted on the bearing 166 integral with the guide 181 is stationary, the said guide being secured to the bracket 127.

A spring 182 secured to a pin 183 projecting from the slide plate and a pin 184 secured to the guide 179 normally urges the plate in the direction of the arrow "XX" so that when the plate is free to move an impact member 185 adjustably secured by set screw 186 to the plate 176 will engage the arm 152 of the rocker member 146 and actuate the lever 141 to operate the cutter.

The pin 184 is stationary, being secured to the guide 179 which in turn is suitably secured to the foot of the bracket 127.

Means are provided to extend or stretch the spring 182 at which time the trigger 164 engages the latch piece 174 and holds the slide plate in operative position so that when the trigger 164 is released the potential energy of the spring will cause the impact member 185 to actuate the lever 141. The above mentioned means for actuating the slide plate 176 so as to extend the spring may comprise mechanism in the form of a rotatable head 187 constituting what may be termed, trigger setting mechanism. The head 187 is mounted on a shaft (not shown) and is continuously driven by suitable motion transmitting mechanism connected with a motor (not shown) which drives the other operating elements of the machine, as for example, the force

rollers 120 and 121 which drive the wire into the coil winding die thus pulling the wire from the spool and causing a rotation of the measuring drum 126.

The head 187 is provided with a projecting pin 188 disposed eccentric to the axis of rotation of the head. This pin is so arranged as to enter a notch 189 in the slide plate 176, thus as the pin rotates with the head the slide plate will be carried in the direction of the arrow "YY" so as to expand the spring and permit the trigger member 164 to engage the latch piece 174 and hold the plate ready for actuation.

It is necessary, however, to provide means for retracting the pin 188 from its operative path after it leaves the notch 189 for holding the same retracted to permit a number of revolutions of the head 187. This is accomplished by making the pin 188 retractable in the head and having a cam face 191 extending from the slide plate 176 in the path of rotation of the pin 188 so that as the pin leaves the notch 189 it will engage a bevel face 192 of the cam and move inwardly until an inner notch on the pin is engaged by suitable mechanism (not shown), which mechanism operates to release the pin again at a definite point of its rotation with the head. This mechanism is clearly shown in the above mentioned patent and further description is therefor believed to be unnecessary herein.

It will be evident from the foregoing that an actuation of the coil cutting mechanism "E" causes a reciprocating movement of the plate 176 and an end 193 of the slide plate is utilized to operate a push rod 194 mounted in bearings 195 and 196 mounted on the bed plate 128 of the coil winding machine. The base plate 10 of the coil stretching machine is so arranged that it may be removably attached to the bed plate 128 of the coil winding machine.

One end of the push rods 194 is provided with a finger 197 and an adjustable contact member 198 is provided at the end 193 of the slide plate 176. Adjacent to the opposite end of the push rod is provided a contact piece 199 engageable with a ward 201 on a slide member 202 which is retained by pins 203 disposed in slots 204. The free end of the slide member is provided with a pawl 205 engageable with the ratchet wheel 43 integral with the hub 41 of the coil stretching machine.

A spring 206 is provided to urge the ratchet into its operative position and the ratchet is provided with the usual spring 207 to hold it for engagement with the ratchet wheel, for the purpose of retaining the carrier of the coil stretching machine against movement. After each actuation of the ratchet wheel an index mechanism is provided including the toothed retainer wheel 44 which is engaged by a dog 208 tensionally held against the said wheel by spring 209.

From the foregoing it will be evident that the present coil stretching device may, as in the illustrated embodiment of the invention, be disposed adjacent to mechanism capable of imparting a reciprocative movement as is the case of the slide plate 176 of the coil cutting mechanism.

In operation therefore the coil winding machine may be actuated to produce a continuous length of coiled filament and with each actuation of the cutting mechanism the carrier of the coil stretching device is operated to position a coil stretching head beneath the guide 53 and as the coil winding machine operates to sever a coiled section of definite length, this coiled section is fed to the coil stretching machine which operates

in synchronism with the coil winding mechanism and stretches coils as fast as they are delivered from the coil winding machine.

The coiled sections, when fed to the coil stretching machine, are as above described, gripped at their opposite ends by suitable jaws, moved through a given path and stretched and then subjected to a heat treatment to set the stretched coil.

10 It will be appreciated that each coiled section being stretched is housed in a heat insulative casing and that such casing is so formed as to maintain a wall surrounding the coil during stretching.

15 It is to be understood that although coils may be stretched by heating in the atmosphere, they may be flashed or formed in a suitable forming gas, in which case the coil stretching device may be enclosed in a bell jar 211 as indicated in dotted lines in Fig. 2 having an inlet 212 for the entrance of a suitable forming gas.

20 Although a preferred embodiment of the invention is shown and described herein it is to be understood that modifications may be made 25 therein without departing from the spirit and scope of the invention as set forth in the appended claims.

What is claimed is:

30 1. A machine for winding and stretching coiled filaments comprising mechanism for helically coiling a filament wire, a plurality of coil stretching devices, means for cutting coiled filament into sections of predetermined lengths, means for feeding said sections, means for moving a stretching device into operation relative with said mechanism, means for depositing a coiled section in a stretching device, means for removing said device, means for positioning another device to receive a coiled section and means for operating 40 said devices to stretch coiled sections therein.

45 2. A machine for winding and stretching coiled filaments comprising mechanism for helically coiling a filament wire, a plurality of coil stretching devices, means for cutting coiled filament into sections of predetermined lengths, means for feeding said sections, means for moving a stretching device into operation relative with said mechanism, means for depositing a coiled section in a stretching device, means for progressively moving said devices into operative relation with said mechanism to receive coiled sections and means for actuating said devices during movement away from said mechanism.

50 3. A machine for winding and stretching coiled filaments comprising mechanism for helically coiling a filament wire, a plurality of coil stretching devices, means for cutting coiled filament into sections of predetermined lengths, means for feeding said sections, means for moving a stretching device into operative relation with said mechanism, means for depositing a coiled section in a stretching device, means for progressively moving said devices into operative relation with said mechanism to receive coiled sections, means for actuating said devices during movement away from said mechanism and means for discharging 55 said stretched sections.

55 4. A machine for winding and stretching coiled filaments comprising mechanism for helically coiling a filament wire, a plurality of coil stretching devices, means for cutting said coiled filament into sections of predetermined lengths, means for feeding said sections, means for moving a stretching device into operative relation 60 with said mechanism, means for depositing a

coiled section in a stretching device, means for progressively moving said devices into operative relation with said mechanism to receive coiled sections, means for actuating said devices during movement away from said mechanism and means for heating said coiled sections while in said stretching device. 80

5. A machine for winding and stretching coiled filaments comprising mechanism for helically coiling a filament wire, a plurality of coil stretching devices, means for cutting said coiled filament into sections of predetermined lengths, means for feeding said sections, means for moving a stretching device into operative relation with said mechanism, means for depositing a coiled section in a stretching device, means for progressively moving said devices into operative relation with said mechanism to receive coiled sections, means for actuating said devices during movement away from said mechanism, means for heating said coiled sections while in said stretching device and means for discharging said stretched sections. 95

6. In combination with a winding machine for producing a continuous length of coiled wire having intermittently operated cutter mechanism to sever said coiled wire into coiled sections of predetermined lengths, a plurality of devices for increasing the lengths of said coiled sections and means controlled by said cutting mechanism for 100 positioning a device to receive a coiled section. 105

7. In combination with a coil winding machine for producing a continuous length of coiled wire having intermittently operated cutter mechanism to sever said coiled wire into coiled sections of predetermined lengths, a plurality of coil stretching devices and means cooperating with said cutter mechanism for effecting a movement of a stretching device to position to receive a coiled 110 section. 115

8. In combination with a coil winding machine for producing a continuous length of coiled wire having intermittently operated cutter mechanism to sever said coiled wire into coiled sections of predetermined lengths, a plurality of coil stretching devices and means for actuating said devices during their travel to stretch coiled sections. 120

9. In combination with a coil winding machine for producing a continuous length of coiled wire having intermittently operated cutter mechanism to sever said coiled wire into coiled sections of predetermined lengths, a plurality of coil stretching devices and means for heating said sections during the stretching operation. 125

10. In combination with a coil winding machine having cutter mechanism to sever a coil into sections, a plurality of devices for increasing the lengths of said coiled sections, and means operating in timed relation to said cutting mechanism for positioning a device to receive the severed section for a stretching operation. 130

11. In combination with a coil winding machine having cutter mechanism to sever a coil into sections, a plurality of coil lengthening devices, and means operating in timed relation to said cutting mechanism to position a device to receive a severed coiled section for a lengthening operation and means for discharging stretched sections. 140

12. A machine for cutting an indefinite length of coiled filament into sections of given lengths comprising a cutter, a reciprocable member for actuating said cutter, a plurality of coil stretching devices and means engaged by said recipro- 150

cable member for moving said devices to receive coiled sections.

13. A machine for cutting an indefinite length of coiled filament into sections of predetermined lengths comprising a cutter, a reciprocable member for actuating said cutter, a conveyor, a plurality of coil stretching devices mounted on said conveyor, means for intermittently rotating said conveyor, said reciprocable member operating to actuate said means.

14. A coil stretching device comprising a tubular casing, coil gripping heads at opposite ends of said casing, means for holding said jaws open to permit the passage of a coiled section endwise into said casing, means for closing said jaws to grip the opposite ends of said coiled section, means for separating said heads to stretch said coiled section and means for heating said stretched section.

15. A coil stretching device comprising a tubu-

lar casing, coil gripping heads at opposite ends of said casing, means for holding said jaws open to permit the passage of a coiled section endwise into said casing, means for closing said jaws to grip the opposite ends of said coiled section, means for separating said heads to stretch said coiled section and means for heating said stretched section.

16. A coil stretching device comprising a telescopic casing, means for holding the casing extended, coil gripping heads at opposite ends of said casing, means for moving said heads toward each other to collapse the casing and dispose the ends of a coiled section within the casing in the gripping heads, means for actuating the heads to grip the ends of the coiled section and means for separating the heads to stretch the coiled section.

JOHN WAHLBERG.
